UNITED STATES PATENT OFFICE.

HERBERT M. DARMSTADTER, OF CHICAGO, ILLINOIS.

FORMILLION.

1,102,729.

Specification of Letters Patent.

Patented July 7, 1914.

Application filed December 16, 1911. Serial No. 666,194.

To all whom it may concern:

Be it known that I, HERBERT M. DARMSTADTER, citizen of the United States, residing at Chicago, in the county of Cook and State of Illinois, have invented certain new and useful Improvements in Formillions; and I do hereby declare the following to be a full, clear, and exact description of the invention, such as will enable others skilled in the art to which it appertains to make and use the same.

This invention relates to a novel construction in what is known as a formillion, an apparatus employed for shaping hats to fit the head, the object being to provide a simple, durable and efficient device of this character which can be easily and readily adjusted and locked in its adjusted position, and consists in the features of construction and combinations of parts hereinafter fully described and particularly claimed.

In the accompanying drawings illustrating the invention: Figure —1— is a top plan view of a formillion constructed in accordance with my invention. Fig. —2— is a central vertical longitudinal section of the same on the line 2—2 of Fig. —1—. Fig. —3— is a fragmentary detail vertical longitudinal section on the line 3—3 of Fig. —1—. Fig. —4— is a fragmentary detail vertical sectional view on the line 4—4 of Fig. —1—. Fig. —5— is a detail perspective view of one of the plunger heads. The present invention consists in details of construction of the device whereby certain advantages are obtained which will appear more particularly from the following specification.

The invention comprises an elliptical frame 1 consisting preferably of an inverted channel-shaped elliptical ring upon which there is mounted at preferably four points, posts 2 secured thereto in a well-known manner by means of the threaded shanks of said posts and the nuts 3 engaging the same, said posts being threaded at their upper ends and engaging in the threaded openings in the thick end portions of channels 4. The latter are disposed parallel with each other at diametrically opposite sides of the frame 1 and in the parallel vertical flanges 5 thereof there are mounted

shafts 6 upon which bell-crank levers 7 are rotatably mounted, one pair of said levers 7 being mounted on each of said shafts 6 and two of the latter carried by each of said channeled members 4. The bell-crank levers 7 of each pair are connected together by means of a cross-bar 8 integral therewith 55 and each pair of said levers 7 is connected together by means of a link 9. One lever 7 of one pair disposed in said respective channeled members 4 is extended to provide an arm 10 by means of which the two pairs 65 of levers 7 disposed between the flanges 5 of one of said members 4 are simultaneously turned on their axes. The said arms or levers 10 are in turn connected together by means of a cross-bar 11 so that by a single 70 movement of said bar 11 all of the bell-crank levers of both channeled members 4 are simultaneously turned. The shafts 6 pass through the elbow portions of said respective pairs of levers 7 and in the other 75 arms of each pair of said levers there is mounted a shaft 12 carrying a roller 13 which is adapted to bear upon a channeled ring 14 coinciding in shape and size with the ring 1 and disposed parallel with and 80 above the same. In the channel of the ring 14 there is contained a gasket 15 of rubber or other suitable relatively soft frictional material between the lower face of which and the upper face of the ring 1 the shanks 85 16 of the heads 17 are clamped, the pressing of the band portion of the hat being effected by means of a hat iron which exerts pressure upon the said heads 17. Supported upon the said ring 1 and disposed around 90 the respective posts 2 are helical compression springs 18 which bear upon the lower face of the web of the ring 14 and yieldingly support the latter. The rollers 13 on the bell-crank levers 7 bear upon the upper 95 face of the ring 14 and serve, when the lever 10 is disposed in the position shown in full lines in Fig. —2—, to depress the said ring 14 against the action of the springs 18 to compress the gasket 15 upon the upper 100 edges of the shanks 16 of said heads 17.

Mounted upon the upper face of the ring 1 at substantially regular intervals over the entire circumference thereof are substantially radially disposed plates or ribs 19 each 105 of which enters a slot 16^a in the lower end

wall of the shank 16 of one of said heads 17 to guide the same, the said shanks 16 being thus substantially radially disposed relatively to the center of the ellipse bordered by said ring 1. The said heads 17 and their shanks 16 are preferably made of sheet metal by stamping or otherwise forming the same, though, obviously, they may be made of any other suitable material such as cast metal, wood and the like. The heads 17 are substantially rectangular in horizontal section having rounded outer faces and flat inner faces. The outer faces of said heads are also tapered so that said heads are of greater depth radially of the ellipse at their lower than at their upper ends, the upper corners of said outer faces being further curved sharply inwardly to meet the upper edges or faces thereof. The shanks 16 of said heads extend from the lower end portion of the inner flat face thereof midway between the side faces or walls of the same, and each thereof is provided with parallel side walls and faces while the upper and lower edges and faces thereof are inclined relatively to each other, that is, the lower face or edge of each shank extends substantially perpendicular to the inner flat face of the head 17 while the upper edge thereof is tapered and converges toward the lower face or edge at the free or inner end of the shank. The taper is made relatively slight for reasons which will hereinafter more fully appear. Each of the said shanks 16 with its head 17 is adapted to be reciprocated radially relatively to the rings 1 and 14 and may be adjusted to any desired position between the limits of movement thereof and when so adjusted may be held firmly in such position by forcing the ring 14 down against the action of the springs 18 thus clamping each of said shanks 16 between the gasket 15 and the upper face of the ring 14. The said rollers 13 when brought down to the position shown in Fig. —2— exert a considerable pressure upon the ring and as the latter is made relatively light the portions thereof contiguous to the rollers 13 will bear more firmly upon the upper faces of the shanks 16 than those parts of the ring 14 which are farther removed from said rollers. The pressure exerted by the ring 14 will obviously become lightest at the points therein contiguous to the ends of the longest diameter of said ring and to equalize this pressure as far as possible with the pressure exerted contiguous to the rollers 13 the said ring 14 is reinforced at the ends contiguous to the longest diameter thereof by means of inverted T-shaped bars 19^a mounted thereon and extending transversely to the channelled members 4. The latter have their webs cut away at two points be-

tween their ends to permit the arms of the levers carrying the rollers 13 to pass freely 65 through the slots or openings 20 thus formed. The said structure above described is adapted to be supported upon an elliptical block 21 which may be either plane, as for example, to receive the flat rimmed straw 70 hats and similarly flat rimmed felt hats which may rest upon said board or the same may be mounted upon a similar block 21 having a convex upper face conforming generally to the shape of the plane of the 75 lower end of any so-called derby or other stiff rim hats. In the latter event, that is, when the device is intended to be used on a block 21 having a convex upper face the rings 1 and 14 are bent in a plane conforming to the plane of the upper face of the block. It is believed unnecessary to particularly illustrate such curvature of the rings as this does not in any manner affect the relative positions thereof or of other 85 parts of the device, or in any manner affect the operation thereof.

Upon the block 21 in the middle or center thereof there is mounted a smaller elliptical block 22 from which two pins 23 project 90 which are adapted to receive a card which has been previously disposed in a conformator and thereby perforated in a well-known manner. Such a conformator for perforating cards is fully described and 95 illustrated in my co-pending application filed August 17, 1911, Serial No. 644,561. This card after being removed from the conformator is cut along the line of perforations therein either slightly outwardly 100 of the latter or on the imaginary line of perforations or slightly inwardly thereof according to the wishes of the person intended to wear the hat treated, that is to say, if the future wearer desires the hat to 105 fit loosely the card is trimmed so as to leave a little material outwardly of the perforations and if he desires a very snug fit it is trimmed on the line of the perforations. The pins 23 are disposed exactly the same 110 distance apart as similar pins in the conformator upon which the card is primarily mounted and perforated. The trimmed card is then placed upon the block 22 so that the pins 23 engage in the holes therein 115 previously made by the pins of the conformator, and the several heads 17 with their shanks 16 are then moved inwardly (while the arms 10 of the bell-crank levers are in the position shown in dotted lines in 120 Fig. —2—) until the inner ends of the shanks 16 contact with the peripheral edge of the card mounted on the block 22 and after all of the same have been properly adjusted to such position the arms 10 are 125 moved down to the position shown in full

lines in Fig. —2—, thus frictionally securing the several heads 17 with their shanks 16 in the position to which they have been adjusted. The said block 21 is also provided with two or more dowels 24 which engage in openings in the cross ribs 25 in the channels of the ring 1 thus accurately positioning the formillion on said block previously to inserting the card upon the pins 10 23. After the heads 17 have been adjusted as described relatively to the trimmed card and secured in such adjusted positions, the hat to be treated is placed or forced upon the device so that the outer faces of the 15 heads 17 contact with the sweat band of the hat. By the application of heat or steam the stiffening in the hat is softened and the band portion of the hat is then pressed with the hot iron and thereupon will retain the 20 shape to which it has been adjusted by the insertion of the heads 17 within the same.

The operation of the device is substantially the same as other formillions heretofore marketed, the improvements residing 25 more particularly in the taper and general form of the shank 16 and in the provision of means whereby all of said shanks 16 are simultaneously locked against movement relatively to the rings 1 and 14 whereby a 30 great deal of annoyance due to movement of said heads 17 out of their adjusted positions prior to their firm engagement between said rings is avoided and the work enabled to be more quickly done. The taper of the shanks 35 16 constitutes an essentially novel feature of the invention inasmuch as said taper practically prevents absolutely the further inward movement of the shanks 16, after the ring 14 has been forced down upon the 40 same, by the pressure applied by the operator upon the heads 17, such inward movement of said shanks being due to a pressure of the hat iron or by the hat itself too great to be resisted by the card against which the 45 inner ends of the shanks bear, and the usual degree of frictional engagement of said shanks between the elliptical rings. The shanks 16 of said heads 17 are relatively thin and as they are sometimes under consider- 50 able strain under which they are apt to spring and bend, they are strengthened and reinforced by means of longitudinal ribs on the sides thereof.

I claim as my invention:

55 1. A device of the kind specified, comprising a base, an elliptical member mounted thereon, a plurality of guide posts projecting from the upper face of said member, a channelled elliptical member vertically mov- 60 able on said posts, the channel thereof carrying a ring of yielding material projecting therefrom and opposing said first-named member, a frame rigidly supported upon the

upper ends of said posts, a plurality of members pivotally mounted on said frame 65 and adapted when turned in one direction to bear upon and depress said movable elliptical member relatively to said frame, a single manually operable lever for simultaneously actuating said members, a plurality of 70 radially disposed vertical guide ribs on said first-named member, a plurality of radially movable heads coacting to provide a substantially vertical elliptical surface and provided with a shank projecting between said 75 elliptical members, each of said shanks longitudinally slotted to receive said ribs and adapted to be guided thereby, said shanks adapted to be held against radial movement as said movable elliptical member is depressed.

2. A device of the kind specified, comprising a base, an elliptical member mounted thereon, a plurality of guide posts projecting from the upper face of said member, a channelled elliptical member vertically mov- 85 able on said posts, the channel thereof carrying a ring of yielding material projecting therefrom and opposing said first-named member, a frame rigidly supported upon the 90 upper ends of said posts, a plurality of members pivotally mounted on said frame and adapted when turned in one direction to bear upon and depress said movable elliptical member relatively to said frame, a single manually operable lever for simultaneously actuating said members, a plurality of 95 radially disposed vertical guide ribs on said first-named member, a plurality of radially movable heads coacting to provide a substantially vertical elliptical surface and provided with a shank projecting between said 100 elliptical members, said shanks having converging upper and lower edges and each thereof having a longitudinal slot in its 105 lower face for receiving said guide ribs, said shanks adapted to be held against radial movement as said movable elliptical member is depressed, and said converging edges 110 adapted to increase resistance of said heads to inward movement relatively to said elliptical members.

3. In a device of the kind specified, the combination with a plurality of adjustable heads adapted to receive the hat for shaping 115 the same, shanks thereon, a ring having ribs for guiding said shanks radially relatively thereto, posts on said ring, a second ring vertically movable on said posts, shanks projecting between said rings, springs normally 120 supporting said last-named ring at the upper limit of its movement relatively to the first-named ring, a pair of parallel channels rigid with said posts, a plurality of levers pivotally mounted on the flanges of said 125 channels and carrying rollers for bearing

upon and depressing the movable ring when said levers are turned in one direction, and a single operating member connected with all of said levers for simultaneously turning the same to depress said ring upon the shanks of said heads.

In testimony whereof I have signed my

name in presence of two subscribing witnesses.

HERBERT M. DARMSTADTER.
